UNITED STATES PATENT OFFICE.

GORTON R. FONDA, OF SCHENECTADY, NEW YORK, ASSIGNOR TO GENERAL ELECTRIC COMPANY, A CORPORATION OF NEW YORK.

PROCESS OF AND APPARATUS FOR ISOLATING ARGON.

Application filed March 19, 1924. Serial No. 700,211.

The present invention relates to the separation of argon from air, and it is the object of my invention to improve the thermal efficiency of a process whereby a gaseous concentrate rich in argon may be produced. From this concentrate, pure argon may be isolated by chemical or other convenient means.

Air contains about 21 per cent oxygen, 10 about 78.1 per cent nitrogen, and about .9 per cent of argon. There are other minor constituents which need not be considered. In order to isolate argon, the air heretofore has been liquefied as a whole, and then subjected to rectification to separate the liquid into fractions which respectively consist largely of nitrogen and oxygen, the rectification process being so carried out that the argon is concentrated either in the nitrogen 20 or in the oxygen fraction. The fraction containing the argon is subjected to a second rectification to concentrate the argon still further.

In accordance with my present invention, 25 I have provided a separation process of greater efficiency by initially liquefying only a part of the air, discarding the unliquefied residue, and producing an argon concentrate from the liquefied portion only.

I have found that a noteworthy concentration of argon occurs as a result of such an initial partial liquefaction. If 5 per cent of the air is liquefied, for instance, I find that the liquid contains about 2.4 per cent 30 argon as compared with about 0.9 per cent which it would have if it had been completely liquefied. As this 2.4 per cent however, represents only about 12 per cent of the original content in air, it is more desirable 35 to liquefy a greater proportion of the air initially, thus maintaining as far as possible the advantage of increased concentration of the argon, but obtaining as well a greater fraction of the available argon.

When about thirty-five per cent of the air 40 is liquefied initially, a liquid is obtained whose argon content has been raised to 1.5 per cent and which represents about 54 per cent of the available argon in the air. As 45 the fraction of the original air input which is liquefied becomes greater the advantage of partial liquefaction necessarily becomes progressively less, so that ordinarily only

about a third of the input of air should be liquefied. 55

My invention includes a new arrangement of apparatus whereby this process may be efficiently carried out.

The accompanying drawing illustrates somewhat diagrammatically two forms of 60 apparatus adapted to carry out processes embodying my invention, and also embodying novel structural features of my invention. Fig. 1 illustrates an apparatus wherein the argon is separated with the nitrogen; and 65 Fig. 2 illustrates an alternative apparatus wherein the argon is separated with the oxygen.

In the apparatus shown in Fig. 1 the condensate produced by partial liquefaction of 70 the air is rectified to produce a liquid consisting largely of oxygen and a gaseous portion consisting largely of nitrogen and containing most of the argon of the original liquefied portion. 75

The operation proceeds as follows: Air at a pressure somewhat above atmospheric pressure and preferably in the range of about two to five atmospheres is supplied by the pipe 4 to the heat interchanger 5, where it 80 is precooled by the cold gases which are being discharged into the atmosphere. The cooled air passes on by means of a conduit 6 to the liquefying pipes 7, which are immersed first in liquid air (formed as later 85 described), the liquid air being replaced when the operation is under way by liquid oxygen which accumulates in the kettle 8 at the bottom of a column 9, at a temperature of about 90 degrees Kelvin. The liquefying 90 conditions are regulated to produce a liquid portion which may constitute about one-third of the original air content (preferably thirty-five per cent) this liquid fraction being passed through the conduit 10 into a coil 95 11, which is immersed in the liquid mixture in the kettle 12 (which consists largely of argon) at the bottom of a column 13, where it is further cooled. The liquid then passes through a conduit 14 into an under-cooling 100 chamber 15, which is maintained at a temperature of about 75 to 77° K. as will be hereinafter more fully described. The pressure of the gas is reduced to a pressure slightly 105 above atmospheric pressure by a valve 2 in the pipe 10. It is introduced at this tem-

perature by a conduit 16 to the top of the column 9 and conveyed in a coil 17 to a region part way down the column 9, becoming progressively warmer until its boiling point is reached at the coil outlet. Below this point rectification takes place in the usual way, contact of the descending liquid and ascending vapors being facilitated by the screens 18. The pure oxygen is drawn off 10 from the bottom of column 9 by means of a conduit 19 containing a valve 20.

As the vapors rising in the upper part of the column come in contact with the coil 17 containing the uncooled liquid, their rectification is carried still further and gaseous nitrogen, with substantially all of the argon in the original liquefied portion of the air, is drawn off from the top of the column 9 by means of a conduit 22 containing a valve 20 23 and is delivered to a coil 24 in the under-cooling chamber 15. A sufficiently low temperature prevails in this cooling chamber to cause the nitrogen-argon mixture to liquefy. The liquid is brought by a conduit 25 into 25 the rectifying column 13 at a point part way down the column 13, as indicated in the drawing, where it is rectified. From the top of the rectifying column 13 a conduit 26 carries the gaseous distillate through a cooling coil 27, where some of the argon which tends to escape with the nitrogen from the top of the condensation column 13 is re-condensed, and returned to the column 13. Gaseous nitrogen is carried by a valved conduit 28 through the heat interchanger 5 into 30 the atmosphere, or it is collected, if desired, in any convenient way.

The argon concentrate, containing small amounts of oxygen and nitrogen, collects as 40 a liquid in the kettle 12 at the bottom of the rectification column 13. Gas from this argon concentrate is drawn off through a conduit 29 containing a valve 30 and is passed through the heat interchanger 5 to increase 45 the thermal efficiency of the apparatus.

The low temperature in the cooling chamber 15 is produced conveniently by a supplementary air liquefier 32 at the top of the column 13, utilizing from $\frac{1}{3}$ to $\frac{1}{2}$ of the 50 unliquefied air from the first rectifier discharged by the conduit 33. Air from this conduit is compressed by a compressor (not shown) and the compressed air is introduced through a conduit 34 the expanded 55 air escaping through a conduit 37. By this expansion part of the air is liquefied in the usual way. The liquid collects at the bottom of the chamber 32, where it overflows through the conduit 38 into the chamber 15. 60 Here it is put under a partial vacuum by a pump exhausting through a conduit 39 so as to boil the liquid at a temperature below the boiling point of pure nitrogen. Its absolute pressure conveniently can be from $\frac{1}{2}$ to $\frac{3}{4}$ 65 of an atmosphere, corresponding to a tem-

perature range of 73.5 to 77° K. By this means a temperature is produced in the chamber 15, sufficiently low to condense whatever gases are passed therethrough, as described.

In order to start the apparatus into operation it is cooled down to liquid air temperature by the expansion of high pressure air. The compressed air enters by a conduit 4 and passes on through the chamber 5, the conduit 6, the pipes 7, the conduits 10, 14 and 16, until it is finally discharged into the atmosphere through the conduit 19. Expansion occurs at the valve 2 until a portion of the air is liquefied and collects in the kettle 8 at the bottom of a column 9. Here the liquid air is converted by rectification to liquid oxygen during operation, as already described.

In accordance with a process described and claimed in my prior Patent 1,527,639 of February 24, 1925, the argon is concentrated in a gaseous nitrogen fraction which is rectified to produce a gas sufficiently high in argon to permit of further concentration by chemical methods. Therefore, generic claims are not made herein, covering broadly the described process of separating atmospheric argon together with gaseous nitrogen from air.

In accordance with an alternate method of operation, the argon is separated first with the oxygen instead of with the nitrogen, the argon being later separated from the oxygen by rectification. An apparatus whereby such a separation may be carried out is illustrated by Fig. 2. The entering air supplied by the valved conduit 4, after passing through the heat interchanger 5, is conducted by a pipe 40 through the coil 41 in the kettle 42 of the column 43 to secure a further cooling, some incidental liquefaction occurring, and then is passed by a pipe 44 through the branched pipes 45 in the kettle 46 of the column 47 to obtain the partial condensation desired. The unliquefied portion of air is discharged as in Fig. 1 by a conduit 19.

The rectification in the column 47 is carried out until the liquid in the kettle 46 contains about 93 to 96 per cent oxygen, a point at which all of the argon originally liquefied is present in this liquid at a concentration of about 5 per cent. When the oxygen constant has risen to this value, the liquid is transferred by a conduit 48 through a valve 49 to an intermediate region in the column 43, where its rectification proceeds in the usual way and as described above. Vapor at the top of the column 43 passes into the undercooling chamber 15, where it is partially condensed in the coil 50, and to aid in the rectification.

Substantially pure liquid oxygen collects in kettle 42 and is drawn off as a gas

through the conduit 53 which is led through the heat interchanger 5. The gaseous argon concentrate is drawn off through conduit 54 from the top of the column. present in atmospheric air and rectifying the fraction through the intermediary of the discarded portion to increase the argon 65 content.

5 Gaseous nitrogen is drawn off from column 47 through a conduit 55, which also is led through the heat interchanger 5. The passage of the liquefied air in the pipes 45 to the coils 56 and 17 by a conduit 16 is similar to the operation described in connection 10 with Fig. 1.

In the description given above, it is understood that the pressure in the rectifying columns is only slightly above atmospheric, 15 being higher in columns 9 and 47 of Figs. 1 and 2 than in the columns 13 and 43 in order to assist in the transfer of the gaseous or liquid product from one column to the next.

20 The figures do not show means for compressing the air used in the argon separation nor compressors and the temperature inter-changers for the portion of air liquefied in the liquefier 32, as these features are implied 25 in all liquid air processes.

In addition to the oxygen and nitrogen obtained, as described above, additional amounts of these gases can be obtained by rectifying in the usual way, the air liquefied 30 for the under-cooling chamber 15.

What I claim as new and desire to secure by Letters Patent of the United States is:—

1. The method of deriving argon from air which consists in subjecting air to liquefying 35 conditions, regulating said conditions to cause the liquefied portion of the air so treated to be less than the unliquefied portion, separating the liquid from the gaseous air, subjecting said liquid to a rectification 40 process to produce liquid oxygen and a gaseous distillate of nitrogen containing most of the argon, reliquefying said distillate and rectifying the same to produce an argon concentrate.

45 2. The method of separating argon from the atmosphere which consists in liquefying about 35 per cent of a given quantity of air, discarding the unliquefied portion, rectifying the liquid portion to produce a liquid 50 consisting largely of oxygen and a gaseous distillate consisting largely of nitrogen and containing most of the argon content of the original liquid portion, reliquefying said gaseous distillate and rectifying the liquid to 55 obtain an argon concentrate.

3. The method of separating argon from the atmosphere which consists in liquefying a part only of a given volume of air, discarding the remaining portion of air, rectifying the resulting liquid to remove oxygen and to produce a fraction containing nitrogen and a higher percentage of argon than is

present in atmospheric air and rectifying the fraction through the intermediary of the discarded portion to increase the argon 65 content.

4. The method of separating argon from the atmosphere which consists in compressing a given quantity of atmospheric air, cooling the compressed air until liquefaction of 70 about one-third of said air occurs, cooling said liquid portion to about 75 to 77° K., rectifying the cooled liquid to produce a fraction consisting largely of oxygen and a second fraction consisting largely of nitrogen and argon, carrying away the oxygen, 75 cooling the nitrogen-argon fraction, rectifying the same to produce a gaseous argon concentrate, recondensing the argon, carrying away the gaseous nitrogen, and finally carrying away an argon concentrate.

5. An apparatus for concentrating argon from air which consists in means for liquefying a portion of an input of air, a conduit for carrying away the unliquefied air, means for producing from said liquid a gaseous nitrogen-argon fraction, a cooling chamber, means for lowering the temperature in said chamber through the intermediary of the unliquefied portion of the original air input, 80 means for liquefying the nitrogen-argon fraction in said cooling chamber, and means for rectifying said liquid nitrogen-argon mixture to produce a concentrate rich in argon. 85

6. An apparatus for producing a concentrate rich in argon from air which consists in means for liquefying a portion only of an input of air, means for carrying away the resulting liquid from the unliquefied portion, 90 means for separately liquefying the latter portion, means for evaporating the resulting liquid under partial pressure, means for fractionating the first portion by successive fractional distillations, and means for condensing the vapors intermediate said distillations through the intermediary of the heat absorption of the aforesaid liquid evaporating under partial pressure. 100

7. An apparatus for separating argon from air which consists in means for in part liquefying a given volume of air, means for carrying away the liquid portion to the exclusion of the gaseous portion, means for further cooling said liquid portion, means for rectifying said liquid to separate therefrom a mixture of gaseous nitrogen and argon, means for recondensing said gases, 110 and means for rectifying the condensate into gaseous nitrogen and a liquid argon concentrate. 115

In witness whereof, I have hereunto set my hand this 18th day of March, 1922.

GORTON R. FONDA.
